UNITED STATES PATENT OFFICE

2,357,574

WORKMAN'S GLOVE

Stuart J. Beebe, Wayne County, Ind., assignor to
 Richmond Glove Corporation, Richmond, Ind.,
 a corporation of Indiana

Application July 20, 1942, Serial No. 451,606

1 Claim. (Cl. 2-161)

My invention relates to improvements in the palm structure of workman's gloves.

The main object of my invention is to provide a reenforcing member over-lying the palm of the glove and serving to protect the normal glove palm against wear and to protect the seam between the thumb-back and the glove palm not only against wear but also against the strains incident to the use of the glove for pulling on ropes or wires extended across the palm.

In accordance with my invention a glove which has been completed in the ordinary way has sewed to it over the entire palm an extra piece of material; this material being sewed to the material of the thumb-back on the thumb side of the seam between the thumb-back material and the palm and being sewed to the palm at the point of juncture at the palm with the fingers. The reenforcing member also over-lying the seam between the back of the glove and the palm in the space lying between the thumb and the index finger.

My invention is illustrated in the accompanying drawing in which,

Fig. 1 is a palm plan of a glove to which my invention has been applied.

Fig. 2 is a plan of the back of the glove to which my invention has been applied.

Fig. 3 is a section taken on the line 3-3 of Fig. 1.

Fig. 4 is an outline of the reenforcing member before it has been applied to a glove.

Fig. 5 is a fragmentary drawing with the thumb lying against the palm.

The glove to which my invention has been applied is here illustrated as having a gauntlet 4 sewed to a palm 5 and back 6 and to the back of the thumb 7. In the particular glove to which my invention is applied, the regular palm piece 5 is sewed to the back 6 along the seams 9 and 10. The front of the thumb 11 is a part of the same piece of material which forms the normal palm of the glove and the fronts of the index and little fingers. The reenforcing piece 12 which constitutes the gist of my invention shaped as shown in Fig. 4, is stitched to the glove palm adjacent the fingers by a double line of stitching 14. It is stitched to the glove palm along the seam between the palm and the back by a line of stitching 15. It has an extension 16 lying between the thumb and the index finger which is sewed to the back of the glove by a line of stitching 17. It is sewed to the palm and to the gauntlet by a line of stitching 18. It is sewed to the normal glove palm by a double line of stitching 19 and to the thumb-back by a double

line of stitching 20. In order that the thumb-back 7 may lie adjacent the palm 5 when the thumb is folded against the palm, the thumb-back is made of a separate piece of material. The 5 seam 21 between the normal palm and the normal thumb-back is entirely covered by the reenforcing member 12, the attachment of the reenforcing member 12 to the thumb-back on the thumb side of the seam 21 and the attachment 10 of the reenforcing member 12 adjacent the finger crotches and adjacent the seam between the normal palm and back relieves the seam 21 from the strain which it usually receives when a glove is used for pulling ropes or wires, particularly where the pull is in the direction across the 15 palm away from the thumb. A tab or extension 16 being attached to the back 6 of the glove and spanning the seam between the palm and the back relieves that seam lying between the 20 index finger and the thumb of strain caused by pulling on ropes or wires in the direction away from the thumb across the palm.

Although my invention is illustrated as applied to gloves having welt seams, it is not necessarily limited to this type of glove, the invention being applicable to any glove in which there is a seam between the glove palm and the thumb-back and which seam is subject to strain as the result of lateral forces applied to the glove palm.

30 What I claim and desire to secure by Letters Patent is:

In a workman's glove, a reenforcing member overlying the palm of the glove and having an extension crossing the seam between the normal 35 palm of the glove and the glove back extending from the thumb to the index finger and attached to the back of the glove, another portion of the reenforcing member being attached to the back of the thumb and overlapping the seam by which 40 the thumb back is attached to the normal palm of the glove, the parts of the reenforcing member remote from the thumb being attached to the normal glove palm adjacent the finger and adjacent the seam between the normal glove 45 palm and the glove back at the point remote from the thumb, a cuff attached to the normal glove palm, one edge of the reenforcing member being attached to the cuff and the glove palm along the seam between the cuff and the glove 50 palm, and a reenforcing member for the palm side of the cuff stitched to the reenforcing member for the palm, and having a fold which protects the stitching between the palm reenforcing member and the cuff.
